WINDSHIELD REGULATOR

Nicholas F. Rund, East Detroit, Mich., assignor
to Ferro Stamping & Manufacturing Company,
Detroit, Mich., a corporation of Michigan

Application October 24, 1932, Serial No. 639,350

12 Claims. (Cl. 296—84)

This invention relates generally to windshield regulators and consists of certain novel features of construction, combinations and arrangements of parts that will be hereinafter more fully described and particularly pointed out in the appended claims.

In the accompanying drawings:

Figure 1 is a perspective view of a windshield regulator embodying my invention applied to a windshield and showing the latter in open position;

Figure 2 is a view similar to Figure 1 but showing the windshield in closed position;

Figure 3 is a horizontal longitudinal sectional view therethrough;

Figure 4 is a bottom plan view of the regulator;

Figure 5 is a fragmentary sectional view taken on the line 5—5 of Figure 1.

Referring now to the drawings, A and B respectively are toggle links for moving the lower edge of a hingedly mounted windshield such as C forwardly and rearwardly relative to a transversely extending flange or rib portion D of a

vehicle cowl E; F and G respectively are upright posts for swinging the arms A and B; H and I respectively are gear sectors projecting laterally from the posts; J is a horizontal stub shaft having a worm K meshing with the gear sectors H

and I and adapted upon being rotated to cause the posts F and G to turn; L is a crank or operating member, and M is a frame attachable to a depending portion or apron N of the cowl and constituting a common support for the regulator parts aforesaid. Preferably the windshield C is

provided at spaced points of its lower edge with rearwardly extending lugs 1 and 2, while the posts F and G are provided at their upper ends with heads 3 and 4 respectively having spaced

upwardly extending lugs or ears 5. The outer sections 6 and 7 of the links A and B are pivotally connected to the lugs 1 and 2 while the inner sections 8 and 9 of the links are connected to hinge pins 10 and 11 respectively extending

through the lugs or ears 5. Preferably the inner sections 8 and 9 of the links are also provided adjacent the hinge pins 10 and 11 with struck-out tongues 12 and 13 respectively that engage the lugs 5 and prevent the links from wabbling or

rattling while in use.

In the present instance the gear sectors H and I are formed integral with the posts F and G respectively. In fact, the post F, head 3 and gear sector H is preferably a die casting, while the post G, head 4 and gear sector I is another die

casting. Thus a minimum of parts are employed and the manufacturing costs have been accordingly reduced. The worm K meshing with the gear sectors H and I is integral with the shaft J and is preferably located between annular flanges 14 and 15 respectively of the shaft. The crank L is conventional in construction and is preferably fixed upon the squared inner end 16 of the shaft J. As a further saving in manufacturing cost the frame M is preferably formed of sheet metal and comprises two elongated complementary sections 17 and 18 respectively having opposed bearing portions 19 and 20 respectively for the shaft J, opposed bearing portions 21 and 22 respectively for the posts F and G, opposed trough-shaped portions 23 and 24 respectively, opposed slots 25 and 26 respectively for the gear sectors H and I, overlapping attaching portions 27 and 28 respectively and overlapping brace portions 29 and 30 respectively. Preferably the opposed bearing portions 19 and 20 for the shaft J receive the flange portions 14 and 15, while the opposed bearing portions 21 and 22 for the posts F and G are constructed in such a way that spaces 31 and 32 respectively are provided upon the inner sides of the posts to permit such posts and the gear sectors H and I integral therewith to shift toward the shaft J to compensate for wear. Suitable followers 33 and 34 respectively and springs 35 and 36 are provided in the opposed trough-shaped portions 24 between the far ends 37 and 38 thereof and the gear sectors H and I for taking up the slack and maintaining the proper engagement between said gear sectors and worm K.

In use the windshield C may be opened or closed as desired by simply turning the crank L. The hinge connections between the heads 3 and 4 of the posts and the inner sections 8 and 9 respectively of the toggle links permit the latter to assume an inclined position while the windshield is open and enables the opening and closing thereof to be effected without any binding action. In this connection it will be noted that the tongues

12 and 13 struck-out from the link sections 8 and 9 will ride upon the lugs 5 when the sections swing about the hinge pins 10 and 11 and will hold the parts against rattling or wabbling. The springs

35 and 36 constantly urge the posts F and G toward the shaft J so that the proper engagement between the gear sectors H and I and worm K will be maintained at all times. Such springs not only take up the slack but also hold the parts in the frame against rattling.

Thus from the foregoing description it will be

readily apparent that I have provided an extremely efficient regulator that is simple in construction, comparatively inexpensive to manufacture, and easy to install and operate.

5. What I claim as my invention is:

1. In a windshield regulator, a supporting frame, an operating member carried by the frame, and means operable by said member for actuating a windshield including a post mounted 10 to turn in the frame and having a head provided with spaced lugs, a hinge pin extending through said lugs, and a laterally projecting member having a substantially tubular portion on the pin between the lugs and having struck-out portions 15 engaging the lugs to prevent the member from wobbling and/or rattling.

2. In a windshield regulator, a supporting frame, an operating member carried by the frame, and means operable by said member for 20 actuating a windshield including a post mounted to turn in the frame and having a head provided with spaced lugs, a hinge pin extending through said lugs, and having means engageable with the lugs in all positions of the member for preventing 25 the said member from wobbling and/or rattling.

3. In a windshield regulator, a supporting frame formed of sheet metal and comprising two 30 complementary sections having opposed bearing portions for an operating shaft, and opposed bearing portions for the rotary post, said last named portions forming elongated slots permitting the post to shift laterally relative to the bearings for said shaft to compensate for wear.

4. In combination, a swinging windshield, a substantially horizontal abutment therefor, and actuating means for the windshield carried by the abutment and including a post mounted to turn about a substantially vertical axis, a lug rigid 40 with and projecting rearwardly from the inner side of the windshield at the lower free edge thereof, and a pair of pivotally connected links pivotally connected to said post and lug, the connection between one of said links and the post 45 including a pivot pin disposed at substantially right angles to the axis of the post and permitting both of said links to move from a position substantially at right angles to the post to a position substantially at an obtuse angle to the post, and the connection between the other of 50 said links and the lug including a pivot element substantially parallel to the inner side of said windshield.

5. In combination, a swinging windshield, a substantially horizontal abutment therefor, and actuating means for the windshield carried by the abutment and including a post mounted to turn about a substantially vertical axis and provided at its upper end with a head having laterally spaced upstanding lugs, a lug projecting rearwardly from the inner side of said windshield at the lower free edge thereof, a pivot pin extending through the laterally spaced lugs and disposed at substantially right angles to the axis of rotation 60 of the post, a pivot element carried by the lug on the windshield and disposed substantially parallel to the inner side of said windshield, and a pair of pivotally connected links having portions respectively sleeved upon the pivot pin and pivot element aforesaid.

6. In combination, a swinging windshield, a substantially horizontal abutment therefor, and actuating means for the windshield carried by the abutment and including a post mounted to turn 75 about a substantially vertical axis provided at

its upper end with a head having laterally spaced upstanding lugs, a pivot pin carried by said lugs and disposed at substantially right angles to the axis of rotation of said post, and a connection between said post and windshield including a link having a portion sleeved upon said pivot pin between said lugs.

7. In combination, a swinging windshield, and actuating means therefor including a post mounted to turn about a substantially vertical axis, a lug rigid with and projecting at substantially right angles rearwardly from the windshield at a free edge thereof, a pair of pivotally connected links, a pivotal connection between one of said links and said lug disposed substantially parallel to one side of the windshield, and a pivotal connection between the other link and post disposed at substantially right angles to the axis of the post.

8. In combination, a swinging windshield, and actuating means therefor including a post mounted to turn about a substantially vertical axis, a lug rigid with and projecting at substantially right angles rearwardly from the rear side of the windshield at its lower edge, a pivot element secured directly to said lug in substantially parallel relation to the rear side of the windshield, a pivot element secured directly to and disposed at substantially right angles to the axis of rotation of said post, and two pivotally connected links respectively connected directly to the pivot elements aforesaid, one of said links being movable about the first mentioned pivot element in substantially parallel relation to said lug, and the other of said links being movable about the second mentioned pivot element from a position substantially at right angles to a position substantially at an obtuse angle to said post.

9. In combination, a swinging windshield, and actuating means therefor including a post mounted to turn about a substantially vertical axis, a lug rigid with and projecting at substantially right angles rearwardly from the windshield, a pivot element carried by said lug in substantially parallel relation to an upright portion of said windshield, a pivot element carried by 110 and disposed at substantially right angles to the axis of rotation of said post, and two pivotally connected links respectively connected directly to the pivot elements aforesaid.

10. In combination, a swinging windshield, a substantially horizontal abutment therefor, and actuating means for the windshield carried by the abutment and including a post mounted to turn about a substantially vertical axis, a pivot pin carried by the post at its upper end and disposed at substantially right angles to the axis of rotation of the post, a connection between said post and windshield including a link having a portion sleeved about said pivot pin whereby said link may move from a position substantially at right angles to the post to a position substantially at an obtuse angle to the post, a pivot pin carried by and disposed substantially parallel to one side of said windshield, and a link terminally connected to the link aforesaid and to the last 135 mentioned pivot pin.

11. In combination, a swinging windshield, a substantially horizontal abutment therefor, and actuating means for the windshield carried by the abutment and including a post mounted to turn about a substantially vertical axis, a pair of pivotally connected links, one of said links being pivotally connected to the windshield, the connection between said link and windshield including a pivot pin carried by and disposed substan- 145

tially parallel to the rear side of said windshield, and the other of said links being pivotally connected to the post, the connection between said last mentioned link and post including a pivot pin carried by and disposed at substantially right angles to the axis of said post, whereby both links may swing relative to the post to compensate for the swinging movement of the windshield.

10 12. In combination, a swinging windshield, and actuating means for the windshield includ-

ing a post mounted to turn about a substantially vertical axis, a pivot pin carried by and disposed substantially parallel to an upright portion of said windshield, a second pivot pin carried by and disposed at substantially right angles to the axis of said post, and a pair of pivotally connected links, one of said links being connected to and movable about the first mentioned pivot pin, and the other of said links being connected to and movable about the second mentioned pivot pin.
